UNITED STATES PATENT OFFICE.

OTTO HABICHT, OF MUHLHEIM-ON-THE-MAIN, GERMANY.

PRESS FOR UNITING THE SOLES AND UPPERS OF SHOES BY GLUING.

Application filed August 1, 1921. Serial No. 489,024.

To all whom it may concern:

Be it known that I, OTTO HABICHT, a citizen of the German Republic, and resident of Muhlheim-on-the-Main, Germany, have 5 invented certain new and useful Improvements in Presses for Uniting the Soles and Uppers of Shoes by Gluing (for which applications for patents have been filed in Germany, H. 81934, July 29, 1920; Austria, 10 March 14, 1921; Switzerland, March 15, 1921; and in France March 19, 1921); and I do hereby declare the following to be a full, clear, and exact description of the invention, such as will enable others skilled 15 in the art to which it appertains to make and use the same, reference being had to the accompanying drawings, and to letters or figures of reference marked thereon, which form a part of this specification.

20 For the sticking together of soles and uppers of shoes by means of glue a bow is used for clamping the uppers and the bottom parts placed upon a last in the press. This bow is directly attached to the heel-end of the last, bearing upon the front or toe part of the same by means of a stud which is bolstered with leather, felt or the like and rests upon the upper of the shoe.

Owing to the high pressure exerted by 30 the press it is unavoidable that with this construction of the bow the upper is damaged notwithstanding the bolster of leather, felt or the like. It happens even frequently that after a certain time of use the surface 35 of the last shows marks or impressions which cause the destruction of the last.

This invention has for its object to obviate 40 this inconvenience in such a manner that the effect of the pressure of the bow upon the upper is avoided by the direct transmission of this pressure upon the front or toe part of the last.

It is indifferent which kind of last is used, the arrangement being adapted to be used 45 with pump-lasts as well as with lasts for shoes having an upper closure extending to the toe.

For the cushion like presser part which bears upon the front part of the last in the 50 apparatus of known construction a pin or stud is substituted according to this invention which engages with a sleeve like cavity of the last in such a manner, that no pressure is exerted upon the upper. The characteristic feature of the invention consists 55 in the direct transmission of the pressure

upon the last, the constructional detail of the arrangement is of no importance as the pin could be fixed in the last designed to engage with a tubular extension of the pressure bow. In lasts for shoes with upper closures extending to the toe a sleeve open at both ends may be arranged at the lower end of the closure, the pin traversing this sleeve to find support in a second sleeve in the 60 lower part of the last.

The pin is preferably adjustably arranged on the presser bow so that the arrangement can be adjusted to the various sizes of the lasts.

In order that the invention may be clearly understood, I shall proceed to describe the same with reference to the form of construction shown by way of example in the accompanying drawing, wherein:—

Fig. 1 is a side elevation partly in section.

Fig. 2 shows in front elevation the arrangement for the adjustment of the pin.

The two parts of the pump last 1 are 80 connected the one with the other by hinge 2 and spring 3. The bow 4 is provided with a pin 5 in a sleeve 6 fixed in the rear part of the last.

According to the invention a sleeve 7 is 85 fixed in the front part of the last which is designed to receive the pin 8 mounted in a supporting piece 9 adjustable in the front end of the presser bow. This supporting piece 9 is mounted (as shown in Fig. 2) 90 on a dove-tailed guide 10 of the presser bow so that the position of pin 8 can be adjusted in accordance with the size of the last.

I claim:

1. In combination a last having a pin 95 socket in its rear portion and a pin socket in its front portion, a shoe press bow, a pin on one end of said bow for engaging the socket in the rear portion of said last, a slide on the other end of said bow and a 100 pin on said slide for engaging the socket in the front portion of the last.

2. In combination, a last having a pin socket in its rear portion and a pin socket in its front portion, a shoe-press bow, a pin 105 on one end engaging the first mentioned socket and a pin slidable on the other end of said bow engaging the latter socket.

In testimony that I claim the foregoing as my invention, I have signed my name.

OTTO HABICHT.
